Attorney

UNITED STATES PATENT OFFICE.

JACOB BROBST, OF SOUTH BETHLEHEM, PENNSYLVANIA.

BRACKET FOR SHADE-ROLLERS.

SPECIFICATION forming part of Letters Patent No. 665,870, dated January 15, 1901.

Application filed April 19, 1900. Serial No. 13,530. (No model.)

To all whom it may concern:

Be it known that I, JACOB BROBST, a citizen of the United States, residing at South Bethlehem, in the county of Northampton and State 5 of Pennsylvania, have invented new and useful Improvements in Brackets for Shade-Rollers, of which the following is a specification.

This invention relates to new and useful improvements in brackets for shade-rollers; 10 and its object is to provide a device of simple construction which may be readily adjusted to rollers of varying lengths and which is constructed of the minimum number of parts.

To these ends the invention consists in providing a base-plate adapted to be suitably attached to the casing of a window and having a stem upon which is slidably mounted the supporting-arm of the bracket. To this arm 15 is secured a spring adapted to project through a perforation within the base of the arm and adapted to engage with one of several similar perforations within the stem of the base-plate.

The invention also consists in so constructing the spring as to permit the same to be 20 readily grasped or operated by the hand.

The invention also consists in the further novel construction and combinations of parts hereinafter more fully described and claimed, and illustrated in the accompanying drawings, showing the preferred form of my invention, and in which—

Figure 1 is a perspective view of a bracket supporting the end of a roller. Fig. 2 is a front elevation of the bracket. Fig. 3 is a 35 central vertical longitudinal section; and Fig. 4 is a transverse section on line xx , Fig. 2.

Referring to said figures by numerals of reference, 1 is a base-plate having suitably-arranged perforations 2 therein for the reception of fastening means, as screws, and this plate is provided with a stem 3, raised above the surface of the base-plate, as shown, and provided with a series of centrally-arranged perforations 4. Slidably mounted upon this 40 stem is a base 5 of an arm 6, which is bent at right angles thereto. This base is provided with inwardly-turned edges 7, adapted to overlap the sides of the stem 3 and serve to retain the same in proper relation. A suitable aperture, as 8, is formed near the end of the arm 45

6 for the reception of the end of the shade-roller 9. A lug 10 is formed upon one edge of the arm 6 and is bent outwardly at right angles thereto and adapted to project through a coil 11 of a spring-wire 12, the end of said 55 lug being bent over the coil to prevent the same from becoming disengaged therefrom. One end of the spring projects into the arm 6 of the bracket, as shown, while its remaining portion is bent downward to a point below the lower edge of the stem 3 and thence upward to a point above a perforation 13, formed within the base of the arm, and is bent inwardly therethrough, as at 14, and adapted to normally engage with one of the perforations 60 4 within the stem 3 of the device. It is obvious that by this construction the arm and its base are securely fastened in position upon the stem. When it is desired to adjust the arm from or toward the end of the stem, it is 65 simply necessary to bear outward upon the curved end of the spring projecting over the edge of the stem, which will thereby release the end 14 from engagement with the stem. The arm may then be slid back or forth and 70 the end 14 sprung into engagement with either 75 of the perforations desired.

By this construction I provide a device which may be readily formed from sheet metal and which is constructed of the minimum number of parts comprising a base and its stem, an arm and its base and lug, and a 80 spring.

In the foregoing description I have shown the preferred form of my invention; but I do 85 not limit myself thereto, as I am aware that modifications may be made therein without departing from the spirit or sacrificing the advantages thereof, and I therefore reserve the right to make such changes as fairly fall 90 within the scope of my invention.

Having thus fully described my invention, what I claim as new, and desire to secure by Letters Patent, is—

1. In a roller-bracket, the combination with 95 a base, of a perforated stem thereto, an arm, a perforated base thereto overlapping the edge of, and slidably mounted upon, said stem, a spring having a coil secured to the arm, and an end of said spring adapted to project 100

through the base of the arm and engage a perforation of the stem.

2. In a roller-bracket, the combination with a base, of a perforated stem thereto, an arm, 5 a base thereto overlapping the edges of, and slidably mounted upon, the stem, a lug upon the arm, a spring secured to the arm and mounted upon said lug, and an end of said

spring adapted to project through the base of the arm and engage a perforation of the stem. 10

In testimony whereof I affix my signature in presence of two witnesses.

JACOB BROBST.
